(57) **CLAIM**

The ornamental design for a portable electronic charging station, as shown and described.

DESCRIPTION

FIG. 1 is a top perspective view of the portable electronic charging station;

FIG. 2 is a bottom view of the portable electronic charging station;

FIG. 3 is a front view of the portable electronic charging station;

FIG. 4 is a back view of the portable electronic charging station;

FIG. 5 is a right side view of the portable electronic charging station;

FIG. 6 is a left side view of the portable electronic charging station;

FIG. 7 is a bottom view of the portable electronic charging station; and,

FIG. 8 is a top view of the portable electronic charging station.

The broken lines present in the figures are included for the purpose of illustrating portions of the article that form no part of the claimed design.
